UNITED STATES PATENT OFFICE.

EDWARD TAYLOR, OF FERRYHILL, ENGLAND.

ENDLESS CONVEYER FOR COAL MINES.

Application filed November 19, 1927, Serial No. 234,510, and in Great Britain March 11, 1927.

This invention relates to endless conveyers as used in coal mines and other like places. These conveyers are usually of considerable length and are supported by a number of 5 transverse rollers or cylinders, a pulley or cylinder at one end of the conveyer around which the belt is passed being driven from a prime mover. This practice with long conveyers results in very heavy strains on the 10 driving pulley owing to the loads supported by the median part of the conveyer. This strain can be appreciably reduced and the general efficiency of the conveyer improved if some or all of the conveyer supporting rollers or cylinders are rotated positively so that 15 the endless belt is supported by a number of live points instead upon a large number of idle rollers, and the conveyer driven at both ends. This is effected by means of my invention which is characterized by the provision upon some or all of the rollers supporting the conveyer, pulleys or the like and driving each of said pulleys by means of an 20 endless cable, belt or the like. In carrying 25 the invention into practice, in the preferred form of my invention each of the cylinders or rollers is provided on its shaft with a pulley, the periphery of which is engaged by a belt, cable or rope passed around pulleys at 30 the loading and the discharging ends of the conveyer, other pulleys are provided at convenient points which can be adjusted to regulate the tension and are in contact with the 35 pulleys of the rope, belt or cable. Suitable guides are provided for the rope, belt or cable to keep it from slipping from position, and these guides have readily movable outer portions to enable the rope, belt or cable to be entirely removed when necessary.

40 In order that my invention may be clearly understood and readily carried into effect, I have appended hereto three sheets of drawings diagrammatically illustrating an embodiment of same and wherein

45 Fig. 1 is a transverse part sectional view of the conveyer.

Fig. 2 shows in end view a pulley for regulating the tension and contact of the roller driving cable.

50 Fig. 3 is a face view of Fig. 2.

Fig. 4 is a side elevation showing the two ends of the conveyer.

Fig. 5 is a plan view of Fig. 4.

55 Fig. 6 is a detail view to a larger scale, showing the arrangement of the cable guides, rollers and pulleys and

Fig. 7 shows diagrammatically a modified method of varying the tension of the driving cable or belt.

Referring to the drawings, more particularly Fig. 1, the rollers 1 and the rollers 2 are arranged in sets each respectively supporting the top and lower portions of the conveyer 3, which is an endless chain, belt or other suitable structure, passed around a 60 large primary roller 4 (see Fig. 4) and a tension adjusting roller 5 constituting the limits of travel of the conveyer 3. The upper and lower sets of rollers 1 and 2 are mounted in any suitable known manner in bearings 6 70 supported by girders 7 extending along the working accommodating the conveyer. I do not propose to enter into a detailed description of the construction and arrangement of the girder 7, the rollers 1 and 2 and the supplying and delivering ends *a* and *b* respectively (see Fig. 4) as these are constructed in accordance with known practice, or may be constructed in any other suitable manner without departing from the spirit and scope 75 of my invention.

The embodiment of my invention illustrated consists in employing an endless cable or its equivalent 8, passed around pulleys 4^a and 5^a mounted on the shafts of the main 85 rollers 4 and 5 hereinbefore referred to. This cable or its equivalent 8 is endless and will drive the conveyer at both ends, and also is adapted to assist the rotation of the rollers 1 and 2 so that the loads carried by the conveyer 3 are assisted at all points of support 90 of the conveyer 3. This is preferably effected by mounting upon the shaft 1^a and 2^a of the rollers 1 and 2, grooved pulleys 9, the upper set of pulleys supporting at the upper 95 parts of their peripheries, the upper part of the cable 8, and the corresponding parts of the lower pulleys 9 supporting the lower part of the cable 8. If the cable 8 is maintained sufficiently taut, the rollers 1 and 2 will be rotated in such manner as to assist the conveyer 3 in its travel instead of merely supporting the conveyer 3 as in present practice.

To ensure the requisite tautness and contact of the cable 8 a suitable number of adjustable pulleys 10 are supported along the girders 7 at convenient points and provided with means for adjusting them in suitable planes. In Figs. 2 and 3, I have shown a suitable form of pulley for this purpose, in which each pulley is supported upon a stub axle 11 through which is threaded an elevating screw 105 110

12 mounted for axial rotation across the horizontal limb of the girder 7, the axle 11 having a yoke shaped inner end 11^a engaging the vertical limb of the girder 7, so that the stub axle can be moved by axial rotation of the screw 12, upwards or downwards. The adjusting pulleys 10 are preferably interposed between the upper and lower pulleys 9 so that in order to increase the tautness and 10 tact of the cable 8 the pulleys 10 will be adjusted downwards. Similar adjusting pulleys 10 will be applied to the upper portion of the cable when and as required.

The adjustment for tautness of the 15 conveyer 3 as well as the cable 8 can be obtained by means of a traversing screw 13 arranged horizontally in bearings at the end of the girder 7 (see Figs. 4 and 5). Axial movement of this screw 13 will move a channel 20 shaped support 14 endwise along the girder 7, this support 14 carrying the bearings 15 of the roller 5. This adjusting gear is preferably duplicated as shown in Fig. 5, so that an equal adjustment may be applied to both 25 sides of the conveyer simultaneously. A further small adjustment can be given either or both sides by means of right and left hand turnbuckles. Alternatively, only one traversing screw 13 may be employed, common to a 30 pair of supports 14. Suitable reduction gear 16 may be employed for rotating the screws 13 by means of swage or ratchet.

It is preferred for the purpose of safety to 35 guide the cable 8 through a suitable number of guides 17, each of which consists of a metal bracket 17^a secured at its lower end 17^b to the girder 7 (see Fig. 1) and having its upper end cranked as at 17^c, said upper end 17^c supporting the upper end of a depending 40 arm 18 pivotally supported as at 19 by the cranked outer end of a bracket 20 secured to the girder 7. The upper end of this arm 18 has provided a slot 18^a (Fig. 6) engaged over a pin 21 carried by the upper end of the member 17, said pin 21 if desired, having a nut 45 threading on to it. By employing guides of this type, the arms 18 can be readily swung so as to expose the cable 8 to enable it to be easily removed when desired.

50 In Fig. 7, is shown diagrammatically how the tension of the driving cable 8 can be adjusted from a common source, which can be an alternative or additional device to the tension adjusting means already described. 55 In this arrangement a cable or rope wheel 8^a is carried by a bogie frame 22 which can be moved and secured any distance, permissible by the cable 8, from the conveyer and can be anchored between the roof and floor. The 60 cable 8 is passed around the wheel 8^a and symmetrically extended over a pair of rope wheels 8^b carried by a frame 23 secured adjacent the conveyer, the cable 8 being carried from the wheels 8^b around the pulleys 9.

65 By means of my invention, the life and

utility of a conveyer is materially increased, and heavy loads will be transmitted with greater ease than at present and for greater distances.

What I claim is:—

1. In an endless conveyer the combination of a primary roller at one end and a tension adjusting roller at the other end, a longitudinal frame, a set of driven rollers supported across said frame parallel with and supporting the lower part of said conveyer, pulleys on the shafts of the primary and tension adjusting rollers, an endless driving member passed round said pulleys and engaged against the upper sides of the peripheries of pulleys on the shafts of the said driven rollers, guards for retaining the endless driving members in the plane containing said pulleys, and a number of tension pulleys pressing said endless driving member downwards. 70 75 80 85

2. In an endless conveyer the combination of a primary roller at one end and a tension adjusting roller at the other end, a longitudinal frame, a set of driven rollers supported across said frame parallel with and supporting the lower part of said conveyer, pulleys on the shafts of the primary and tension adjusting rollers, an endless driving member passed round said pulleys and engaged against the upper sides of the peripheries of pulleys on the shafts of the said driven rollers, pairs of vertical guides between which said endless driving member is passed to maintain it in the plane containing said pulleys, screw adjusted tension pulleys pressing said endless driving member downwards against the upper sides of the pulley of the lower set of driven rollers, and screw means for adjusting the tension of the conveyer. 90 95 100 105

3. In an endless conveyer, the combination of a primary roller at one end and a tension adjusting roller at the other end, a longitudinal frame, a set of driven rollers supported across said frame parallel with and supporting the lower part of said conveyer, pulleys on the shafts of the primary and tension adjusting rollers, an endless driving member passed round said pulleys and engaged against the upper sides of the peripheries of pulleys on the shafts of the said driven rollers, a plurality of vertical brackets each having spaced from it but substantially parallel with it a pivoted arm between which arms and brackets the endless driven member passes, and a number of tension pulleys pressing said 110 115 120 endless driving member downwards.

4. In an endless conveyer, the combination of a primary roller at one end and a tension adjusting roller at the other end, a longitudinal frame, a set of driven rollers supported across said frame parallel with and supporting the lower part of said conveyer, pulleys on the shafts of the primary and tension adjusting rollers, an endless driving member passed round said pulleys and engaged 125 130

against the upper sides of the peripheries of pulleys on the shafts of the said driven rollers, a plurality of vertical brackets each having spaced from it but substantially parallel 5 with it a pivoted arm between which arms and brackets the endless driven member passes, screw adjusted tension pulleys press-

ing said endless driving member downwards against the upper sides of the pulley of the lower set of driven rollers, and screw means 10 for adjusting the tension of the conveyer.

In witness hereof I have signed this specification.

EDWARD TAYLOR.
